DESIGN FOR A COOKING STOVE OR SIMILAR ARTICLE

Merrill J. Woods, Indianapolis, Ind.

Application August 17, 1945, Serial No. 121,477

Term of patent 14 years

(CL. D81—4)

To all whom it may concern:

Be it known that I, Merrill J. Woods, a citizen of the United States, residing at 345 Campbell Avenue, Indianapolis, in the county of Marion and State of Indiana, have invented a new, original, and ornamental Design for a Cooking Stove or Similar Article, of which the following is a specification, reference being had to the accompanying drawing, forming part thereof.

The figure is a perspective view of a cooking

stove or similar article, showing my new design.

The dominant features of the design reside in the portions shown in full lines, and the left-hand side of the structure is substantially identical to the right-hand side illustrated.

I claim:

The ornamental design for a cooking stove or similar article, as shown and described.

MERRILL J. WOODS.
